UNITED STATES PATENT OFFICE.

LEVI W. MALLORY, OF PHILADELPHIA, PENNSYLVANIA, ASSIGNOR TO
WM. MORRIS.

IMPROVEMENT IN OMNIBUS-REGISTERS.

Specification forming part of Letters Patent No. 11,148, dated June 20, 1854.

To all whom it may concern:

Be it known that I, LEVI W. MALLORY, of the city and county of Philadelphia, and State of Pennsylvania, have invented a new and useful Machine for Registering the Fares received by Drivers of Omnibuses or other Vehicles, called "An Omnibus-Register;" and I do hereby declare that the following is a full, clear, and exact description of the construction and operation of the same, reference being had to the annexed drawings of the same, making a part of this specification, in which—

Figure 1 is an elevation of the interior of the register. Fig. 2 represents the dial as seen by the passengers in the coach; Fig. 3, the private or recording dials accessible to the proprietor.

Similar letters of reference in the several figures denote the same part of the machine.

In the drawings, A is the main or driving wheel acted upon by click C in connection with rod E, lever G, and rod or handle H. This handle H is used by the driver when he receives his fare. He records the fare by pulling the handle H, when a motion is given to the whole machine. The lever G and rod E and click C are raised, so that wheel A is turned one ratchet forward, and the same is registered on the dials, Figs. 2 and 3. Wheel A has fifty ratchets.

B is a wheel of thirty ratchets moved by pin Y on wheel A. Thus at one revolution of A the wheel B is moved one ratchet or notch forward, signifying that fifty fares have been registered. (See Fig. 3.)

C is a click held to its position by spring D for the purpose of moving wheel A, as described.

E is a rod attached to lever G, to which are riveted click C and spring D.

F is a slide or rest for rod E; G, the main lever, to which is attached rod J. Thus when H is pulled J is raised and the bell-hammer K is raised also until it leaves the notch in rod J, when it is forced back to its position by spring W, causing it (K) to strike the bell L, thus assuring the passengers that the fare has been registered.

M, N, O, P, Q, and U compose what I term a "trigger" or "catch," and is an important part of the whole, as it prevents the possibility of

ringing the bell without registering the fare. Thus it will be seen when the hammer K has been drawn up by rod J the rod M, working through slide or rest Q, is also forced up by spring U working under the lever N, to which is attached the coupling O, connecting said lever and the trigger P. Thus if the driver pulls the handle H the trigger P flies up around the screw in its lower extremity, so as to bring its notches under the rod J and prevent it (J) from coming back until the fare has been registered and the bell struck. Without this trigger or catch the bell could be struck without registering the fare by simply drawing the handle part up and letting it fly suddenly back, thus entirely defeating the object of the machine; but with this trigger the fare is registered before the bell is struck, thus preventing fraud on the part of the drivers. When the hammer K leaves the notch in rod J, it strikes upon rod M and forces the trigger back to its position, as set forth in Fig. 1.

T T T are springs serving to hold the wheels in their position; S, spiral spring to draw the rod J to its position under the bell-hammer; Z, bed-plate for the whole; R, a spring serving to hold the rod J to the hammer until the wheel A has been moved forward one notch or ratchet; X X, the pinions or axles of the wheels, to which are attached the index-hands. (See Fig. 3.) To the pinion of wheel A is also attached the large hand seen on dial, Fig. 2.

The whole is firmly attached to bed-plate Z, the front of which is suitably lettered, viz.: "Passenger-register," "Passengers will please observe that the driver rings the bell upon receipt of each fare."

What I claim as my invention, and desire to secure by Letters Patent, is—

The combination of the rod M, guide Q, lever N, spring U, coupling O, and eccentric ratchet or trigger P, operating substantially as set forth, to prevent the ringing of the bell until the fare is registered.

In testimony whereof I have hereunto signed my name before two subscribing witnesses.

LEVI W. MALLORY.

Witnesses:

ROB. GANE,
J. WILKINSON.
